FRANK E. FARNHAM, OF PROVIDENCE, RHODE ISLAND.

GEM-SETTING.

1,030,990.

Specification of Letters Patent.

Patented July 2, 1912.

Application filed December 9, 1911. Serial No. 664,788.

To all whom it may concern:

Be it known that I, FRANK E. FARNHAM, a citizen of the United States, residing at Providence, in the county of Providence and State of Rhode Island, have invented certain new and useful Improvements in Gem-Settings, of which the following is a specification, reference being had therein to the accompanying drawings.

10 My invention relates to gem settings and to the special details of their construction as set forth in the claims.

In the accompanying drawings, like reference letters indicate like parts.

15 Figure 1 is a perspective view of my improved gem setting. Fig. 2 is a view of the same as seen partly in elevation and partly in diametrical section. Fig. 3 is a view, as seen partly in elevation and partly

20 in diametrical section, showing said setting and a gem secured in wearing position therein. Fig. 4 is a view of said setting and gem as seen in elevation. Fig. 5 is a top plan view of the gem and the prongs of 25 the setting bent thereon. Fig. 6 is a view, partly in elevation and partly in diametrical section, showing my improved gem setting having its seat adapted to support either a flat or semi-oval, or other gem, which has

30 a straight base or a faceted gem which has a pyramidal or conical base. Fig. 7 is a view of the gem setting having such a seat, as seen partly in elevation and partly in diametrical section, and shows a faceted

35 gem mounted therein, which has a pyramidal or conical base. Fig. 8 is a like view, showing a precious stone mounted therein, which has a flat bottom and which is semi-oval in cross section. Fig. 9 is a like view, showing

40 a precious stone mounted therein, which has a flat top and a flat bottom parallel with each other. Fig. 10 is an isometric view and Fig. 11 is a top plan view of a modified form of my improved gem setting.

45 The distinguishing feature of my improved gem setting is that it has a ring or support, made with integral solid prongs to cramp or bend over upon the face of the gem to confine it in position. These prongs are

50 formed from a ring-shaped blank and swaged by die-action so as to cause the metal thereof to flow, by cold pressure, in the die, under the force of a plunger, to form a series of ridges upon and across the exterior 55 surface of the blank, which ridges terminate, respectively, in pointed prongs, according

to the matrix of the die. These prongs are afterward bent to bring the inner surface of each parallel with the axial line of the ring, and by proper tools the circular setting 60 thus formed can be made oval, or polygonal, or in other shapes, by die and plunger, as is well known in the art.

In Fig. 1 A represents the ring-shaped body or base of the gem setting, provided 65 with a series of prongs B, parallel one with another. The inner surface of the body A, at and near its top, is made with an annular angularly-inclined seat C. Each prong B has a tapering base or ridge b, whose central 70 longitudinal line is in alinement with the central longitudinal line of the prong B. These base ridges b project from the cylindrical surface of the body A in radial directions as shown. The tip of each prong B 75 has its transverse surface b' shaped to extend in an obtuse angle with the outer edge of the prong, so that at the extremity of said tip or terminal the angle is acute or slightly rounded. The gem is shown at D 80 and may have facets d, as usual.

In Figs. 3, 4 and 7 the gem has a conical or pyramidal base d', which may or may not be covered with foil in the well-known manner.

85 As seen in Fig. 3, the gem D is placed within the ring-shaped setting A and rests upon the seat C thereof. The prongs B are then bent over into contact with the gem to cramp and secure the same in position, as 90 illustrated in Figs. 3, 4, 5 and 7.

The shape of the ridges b is shown in front elevation in Figs. 1 and 4, and in side elevation in Figs. 2, 3, 6, 7, 8 and 9. It is evident that as the ridges b and prongs B 95 stand radially outward, and as the body or ring A of the setting is of less diameter than the diameter of the gem D, said gem is well displayed, and a comparatively large portion of its surface is visible, and also the 100 edge of the gem projects considerably outside of the ring or body A, thus allowing a better illumination of the gem, because the light can shine unobstructed through the edge thereof and the adjacent portions of 105 the gem.

The beauty of the gem is much enhanced by reducing to a minimum the extent of the metal surface ordinarily visible, as plainly illustrated in Fig. 5. As the whole of the 110 body or base A of the setting is so far in from the edge of the gem as to be incon-

spicuous in an ordinary glance, and the prongs are equispaced and radially spread, there are the broad intervals between said prongs where the gem D is shown unobstructed. It is particularly noticeable that 5 the prongs B are bent into the closest possible contact with the facets *d* of the gem so as not to present any sharp points to catch into lace or other fabric of clothing, and especially that when the prong B is so bent 10 the upper edge *b'*, as represented in Fig. 4, is horizontal to the central facet of the gem D.

In Figs. 6, 7, 8 and 9, the same setting is 15 shown, with the exception that, in addition to the sloping seat C, there is provided a concentric flat annular seat F. By this construction the setting is adapted to be used for the mounting of precious stones which 20 have either flat, or pyramidal, or conical bases. Thus, in Fig. 7, a faceted gem G is set, whose base is pyramidal. In this case the gem G rests upon the sloping annular seat C, but does not touch the annular flat seat F. In Fig. 8, a precious stone H has a 25 semi-oval top and a flat bottom. This flat bottom rests upon the flat annular seat F and not upon the sloping annular seat C.

In Fig. 9 a precious stone I is mounted, 30 whose top and bottom surfaces are flat and parallel with each other. It rests upon and is supported by the flat annular seat F, but not upon the sloping annular seat C. Gem settings with these two seats are a new article 35 of manufacture, and enable the use of the same setting with gems having bases of different kinds.

As many prongs can be made as are desired, 40 by dies shaped for the purpose. Precious stones having three edges may be held by three prongs; square or four-edged stones may be held by four or eight prongs, and stones having round, oval, or polygonal edges may have any desired number of 45 prongs, three or more. As a modification of the gem setting shown in Fig. 1, which has a circular or ring-shaped base, the invention is illustrated in Figs. 10 and 11, where is 50 seen a square gem setting. In Fig. 10, the base A' is square and the ridges across said base and the projecting terminals of those ridges are the same as in Fig. 1. In Fig. 11 a square gem D' is represented, held or set 55 in place by the bent prongs.

In order to change the round or ring-shaped setting represented in Fig. 1 into the square setting shown in Fig. 10, it is 60 only necessary to subject the round, ring-shaped setting to the operation of a plunger, which is square in cross section, coöoperating with a die of corresponding shape. Thus the ring-shaped base shown in Fig. 1 is the common stock and may be provided in numbers as a jeweler's finding and a new article 65 of manufacture, to be formed into non-

circular settings by means of suitable dies and plungers, and in this manner, triangular, square, or polygonal settings may be made, or elliptical, oval, semi-oval, crescent, or other forms.

It is usual in this art, when prongs are used upon gem settings, either to form such prongs separately and to solder each one to the body of the setting (in which case, the prongs and the body of the setting are 75 softened by the heat of such an operation and thereby made weak and inefficient and non-durable); or to form such prongs integral with the body portion by cutting a single blank from one piece of sheet metal 80 (in which case either the prong is too thick because the body portion must have rigidity and strength to perform its functions, or else the body is too thin to serve its purposes, because the prongs must be flexible and able 85 to bend into close contact with the gem).

In my improved gem setting, the body is very rigid and substantial, and the prongs are graduated in thickness, being tapered thinner toward the tip, so as to avoid any 90 danger of catching the threads of the lace or other fabric of the garment. These prongs are easily bent to lie snug to the face of the gem, but at the place of flexure have sufficient stock to maintain whatever shape 95 they are bent into. They are especially strong, because of the swaged ridges *b*, and securely confine the gem in place. The symmetrical spacing and the tapering shape of these ridges enhance the beauty of the 100 setting which holds the gem.

I claim as a novel and useful invention and desire to secure by Letters Patent:

1. The improved gem setting herein described, consisting of a body portion having 105 a series of integral, solid cold-swaged prongs extending radially across the outer surface of the body portion at right angles to the base thereof and projecting from the opposite edge of the body portion.

2. The improved gem setting herein described, consisting of a body portion having a series of integral, solid cold-swaged prongs, whose bases extend radially across the outer surface of the body portion at 115 right angles to the base thereof and are radially thicker than the body portion and whose tips project from the inner peripheral edge of the body portion and are graduated so as to be thinner toward their outer ends.

3. The improved gem setting herein described, consisting of a body portion having a series of integral, solid, cold-swaged prongs, radially arranged and extending transversely across the outer surface of the body portion at right angles to the base thereof and projecting beyond the opposite edge, such projecting part of each prong diminishing in thickness toward its free, outer end and there terminating with an 130

inwardly and radially directed, longitudinal edge, which last named edge is at an obtuse angle with the outer edge of said prong, and which angularly-directed edge, when 5 the prong is bent to cramp a gem in position, is parallel with the outer rim of the body portion.

4. The improved gem setting herein described, consisting of a body portion having 10 at and near one annular edge thereof on the inner surface of the same an annular seat sloping radially toward the center of the body portion; and a series of cold-swaged solid prongs, integral with the body portion 15 and extending across the outer surface of the body portion at right angles to the base thereof and projecting beyond said annular edge thereof.

5. The improved gem setting herein described, consisting of a body portion, having 20 at and near one annular edge thereof on the inner surface of the same an annular seat adapted to support a gem; and a series of swaged prongs, integral with the body portion 25 and extending across the outer surface thereof and projecting beyond said annular edge.

6. The improved gem setting herein described, consisting of a body portion having, 30 at and near one annular edge thereof on the inner surface of the same, two annular seats, one of which, nearest said annular edge, has a flat bottom, and the other of which is adjacent to and below the said flat bottom of 35 the first named seat and has an annular seat sloping radially toward the center of the body portion, and a series of cold-swaged prongs, integral with the body portion and 40 extending across the outer surface thereof and projecting beyond said annular edge.

7. As a new article of manufacture, a jeweler's finding consisting of a ring-shaped base having integral therewith a plurality of solid projecting gem-holding prongs in series, which are terminals of radial ridges 45 upon the exterior surface of said base, integral therewith and extending at right angles, respectively, with the edges of said base.

8. In a gem setting, the combination of 50 a body portion comprising a base of uniform thickness throughout, an integral continuous flange upon the base of less thickness than that of the base thus leaving a sloping seat along the inner surface of the 55 base just below the bottom of said flange, and a series of cold-swaged ridges integral with said base and flange and extending transversely upon the outer surface of said base and flange and terminating above said 60 flange in gem-setting prongs.

9. The improved gem setting herein described, consisting of a ring-shaped base having at one outer edge thereof an integral continuous flange and provided on its inner 65 surface with two seats one of which contiguous to said flange has a flat bottom and the other of which adjacent to said flat bottom has an inwardly sloping seat; and a series of cold-swaged prongs integral with 70 said base and extending across the outer surface thereof and projecting beyond the said flange.

In testimony whereof I affix my signature in presence of two witnesses.

FRANK E. FARNHAM.
